Primary Examiner — Patricia A Palasik*(74) Attorney, Agent, or Firm* — HOFFMANN AND BARON, LLP(57) **CLAIM**

The ornamental design for a wearable robotic exoskeleton, as shown and described.

DESCRIPTION

FIG. 1 is a top back perspective view of a wearable robotic exoskeleton showing our new design;

FIG. 2 is a front plan view thereof;

FIG. 3 is a back plan view thereof;

FIG. 4 is a top plan view thereof;

FIG. 5 is a bottom plan view thereof;

FIG. 6 is a left side plan view thereof; and,

FIG. 7 is a right side plan view thereof.
